EMIL DEISTER, OF FORT WAYNE, INDIANA.

APPARATUS FOR CONCENTRATING MATERIALS, SUCH AS COAL.

Application filed November 28, 1924. Serial No. 752,800.

The invention relates to dry concentrating tables of the differentially reciprocated, transversely inclined type whereon stratification of the materials is accomplished by air 5 under pressure.

It is a well recognized fact that, when particles of matter of about the same size but of different density fall through quiescent air, those particles of greatest density 10 attain a greater velocity than those of less density. Therefore, when the particles come to rest some stratification of the same occurs—the heavier particles being at the bottom, the next lighter next above, etc. Also, 15 if two particles of matter of about the same shape and density but of different sizes fall through quiescent air the larger particle will attain the greater velocity since the resistance of the air is proportional to the cross- 20 sectional area of the particle and such resistance is proportionally greater on the smaller particle.

Prior dry concentrating tables for concentrating ore, cleaning coal, sizing and 25 separating comminuted materials, etc., have been constructed with pervious surfaces on their decks through which air under pressure ascends, together with impervious channels in the surfaces. The material to be 30 sized or separated is passed over these surfaces. The ascending air tends to float the materials and stratification thereof on the surface and in the channels follows. The lighter particles settle with the heavier particles 35 in the channels and travel with the latter in the channels under the influence of the reciprocating movement of the table. The lighter particles pass over the sides of the channels as the bed of materials in the 40 channels increases in depth or the channel decreases in depth. To accomplish this flotation and stratification, however, air under considerable pressure is required and careful previous sizing of the material is 45 essential so that each particle shall have about the same cross-sectional area. The separation of the material on the table is, therefore, relatively slow and incomplete and its capacity is relatively small.

50 I have found that a dry concentrating table is more efficient and a cleaner concentrate is obtained when the lighter particles are not only rendered buoyant but are propelled by air under pressure toward the 55 edge of the table at which they are to discharge, and the object of my invention is

to provide a reciprocating, transversely inclined table by which the materials to be concentrated are caused to cascade down the transverse slope thereof and subjected to lateral jets of air under pressure which maintain a constant positive transverse movement of the lighter particles toward the intended discharge point therefor, the heavier particles being collected in channels and conveyed off the table by the longitudinally reciprocating movement of the table.

Another object is to provide a reciprocating, longitudinally channeled table with means whereby air under pressure is caused 70 to pass transversely through the channels for agitating the materials caught therein and causing the upper strata thereof to move laterally therefrom while the heavier particles are conveyed in the channels under the 75 influence of the reciprocating movement of the table.

Another object of my invention is to provide an efficient transversely inclined dry 80 concentrating table with novel means on the surface of its deck by which the materials are caused to travel over a series of cliffs or precipices extending longitudinally along the transverse slope of the deck and gentle jets of air are caused to pass laterally 85 through the falling particles at each precipice for effecting a stratification of the same and causing the lighter particles to move down the said slope.

An embodiment of the invention is illustrated in the accompanying drawings in which—

Figure 1 is a plan view of a table embodying the invention; Fig. 2 a side elevational view of the same; Fig. 3 a cross-section on line 3—3 of Fig. 1; Fig. 4 an enlarged cross-section on line 4—4 of Fig. 1; Fig. 5 a fractional view of the surface of the deck taken in the direction of the arrow in Fig. 4; Fig. 6 a bottom plan view of a fraction of one of the air channel forming members; Fig. 7 a side view of the said member, taken in the direction of the arrow in Fig. 6; Fig. 8 a cross-section similar to Fig. 4 illustrating a modified form of riffle and pervious deck; Fig. 9 a side view of the same taken between and in the direction of the arrows in Fig. 8; Fig. 10 a plan view of one of the air channel forming strips of Fig. 8; Fig. 11 a side view of the strip and Fig. 12 a vertical cross-section of one of the supports for the table.

Referring to the illustrative embodiment of the invention, 1 represents the fixed frame of the table upon which a differential driving mechanism 2 is mounted and upon which 5 are also mounted the supports 3 in sufficient number. At the upper end of each support is a transversely concaved plate or base 4 upon which is slidably engaged a member 5 having a lower convex surface. Each 10 member 5 is secured to and depends from the deck 6 of the table. The driving mechanism is suitably connected to the deck for causing it to differentially reciprocate longitudinally, a spring 7 opposing the rearward 15 movement of the deck.

The deck is preferably hollow the base 8 being horizontal transversely and the two 20 relatively steep sides 9 and 10 sloping downwardly in opposite directions from their junction to the base 8. The base 8 is impervious and a conduit 111 to which air under pressure is supplied is connected by the flexible conduits 12 to the deck by which the air under pressure is supplied to the air box 25 within the deck and formed by the base 8, the two sloping sides 9 and 10 and by suitable end members, 8^a.

The sides 9 and 10 form the top of the deck 30 of the table. The two top sections are alike in construction except that the parts of one are arranged in reverse order to that of the other since the sections slope in opposite directions. Each section is formed of a series of parallel ribs 12^a, Fig. 4, extending from 35 the head or motion end 13 of the table toward the foot or discharge end 14. The outer portion of each rib is triangular in cross-section, and secured to the upper surface of said triangular portion is a series of 40 corrugated strips 15 extending along the rib. Preferably, these strips are formed of rubber, such as stair-tread material, and each strip is so cut that the corrugations are diagonal relatively to the length of the strip, 45 as shown in Fig. 6, so that when the strips are in position the ducts 16 therein are diagonal to the line of reciprocation of the table. In Figs. 3 and 4 the approximate inclination of the surface of the deck is shown and in 50 Fig. 4 the parts are in substantially full size. The inner ends of the ducts communicate, through the spaces between the ribs, with the air box and hence cause the air to discharge from the air box in jets oblique 55 to the line of reciprocation of the table as shown by the arrows in Figs. 1 and 4, and since the slope of the top surface of the deck is relatively steep the jets approach the horizontal in the operating position of the 60 table.

A strip 17 on the top of the series of corrugated strips is suitably secured to the rib below it, and it may be secured to the next rib above against which it abuts. This 65 strip may have any desired shape or form,

a number of forms of the same being illustrated in Fig. 4. The top face of each strip forms one side wall 18 of a channel A that extends from the head end of the table toward the discharge end 14 and the outer face of the rib together with the corrugated strips forms the other side wall 19 of the channel, the said side wall being pervious in its upper portion. Each channel is oblique to the line of reciprocation of the table—it extends upwardly on the transversely sloping top of the deck.

In order to save air and to cheapen the construction of the table I attach a high board or guard 20 at each lower rear corner 80 of the deck, the board extending from a suitable or selected point in the head end to the discharge side 21, and I close off the triangular section 22 rearward of the board so that no air will pass through it. A board 23 extends along the ridge of the deck and high boards or guards 24 extend down the oppositely declined surfaces of the deck from a selected point in said ridge board to the discharge ends 14, at suitable points above the lower forward corners of the deck. The boards 24 hold back or buck the materials. The triangular spaces 25^a are impervious and 85 perform no function. They could be omitted but the table is more economical and convenient to build with them than without them.

The channels A terminate at the high guards 24 and at the lower portion of the discharge ends 14. Some of the channels 90 begin at the head end of the deck, others at the boards 20 and still others at the discharge sides 21.

In the modified form shown in Fig. 8, which for a great many uses is the preferred 100 form, the corrugated strips 25 are separated by wooden strips 26 and each series of strips is secured on the upper face of a rib 27, the uppermost wooden strip being engaged 105 on the outer face of the next rib above. The outer edges of the strips are flush with the outer face of the ribs upon which they are secured. An angle bar 28 of suitable material is secured to the uppermost wooden strip and to the rib above and forms the bottom of 110 a channel that is oblique to the line of reciprocation of the table. As in the previously described form of channel, a portion of its upwardly extending wall is pervious, since the oblique channels 29 form ducts that communicate with the air box and outside air. The outwardly projecting arm of each angle member 28 may overhang the pervious wall 115 of the channel.

The table is supported so that its transversely sloping sides also slope downwardly 120 longitudinally toward the discharge ends 14. The materials to be treated are fed through a hopper 30 that is disposed over the ridge board adjacent to the head end of 125 130

the table. They are deposited onto both declined top surfaces and under the influence of gravity tend to travel down each slope toward the discharge sides 21. The materials drop or cataract over the pervious walls of the channels in succession and as they fall the jets of air at each channel are projected obliquely and laterally through the sheet of materials, carrying the lighter particles to the rim of the precipice below. The heavier particles settle into the channel. As the materials continue their cataracting movement down the slope, more and more of the heavier particles are caught in the channels and which under the influence of the differential movement of the table are conveyed in the channels toward the forward ends of the same. As the channels fill up the upper strata escape over the sides thereof and fall over the precipices, more and more of the lighter particles being advanced down the transverse slope of the deck. The heavier particles eventually travel down the slope along the high boards 24 and pass off the table at the discharge ends 14, and the lighter particles, such as coal, eventually reach the discharge sides 21 of the table and leave the table at those sides.

30 One wall of each channel being more or less pervious, the collecting of the lighter particles in the channels is avoided, since the jets of air are directed through the upper strata of the materials that collect in the channels.

In practice the channels and the precipices will be disposed on the deck at a suitable angle to the direction of reciprocation of the table. The diagonal arrangement of the same shown in the drawings is preferable since it affords a large capacity for the table.

It will be seen that the operating portion of each top surface of the deck consists of a series of longitudinal steps, the treads of which are impervious and the risers of which are perforated, the tread and a portion of the riser above forming a channel.

Various arrangements and constructions of the parts constituting the deck will be suggested to one skilled in the art, the construction and arrangement shown being only illustrative of the invention.

What I claim is:

55 1. A dry concentrating table comprising a differentially reciprocated, transversely inclined deck, means to feed material to be concentrated to the deck, an air box within the deck for air under pressure, a series of channels in the transversely inclined surface of the deck extending longitudinally thereof and corrugated strips in one wall of each channel which form ducts communicating with the air box and leading laterally therefrom to the exterior, said wall also forming

ing the abrupt wall of a precipice contiguous to the channel next above.

2. A dry concentrating table comprising a differentially reciprocated, transversely inclined deck, means to feed material to be concentrated to the deck, an air box within the deck for air under pressure, a series of channels in the transversely inclined surface of the deck extending longitudinally thereof in a direction oblique to the line of reciprocation of the deck, and corrugated strips in one wall of each channel which form ducts communicating with the air box and leading laterally therefrom to the exterior, said wall also forming the abrupt wall of a precipice contiguous to the channel next above.

3. A dry concentrating table comprising a differentially reciprocated, transversely inclined deck, means to feed material to be concentrated to the deck, an air box within the deck for air under pressure, a series of channels in the transversely inclined surface of the deck extending longitudinally thereof in a direction oblique to the line of reciprocation of the deck, and corrugated strips in one wall of each channel which form ducts communicating with the air box and leading laterally therefrom to the exterior, the ducts being oblique to the longitudinal axes of the strips, said wall also forming the abrupt wall of a precipice contiguous to the channel next above.

4. In a dry concentrating table a deck consisting of a transversely inclined frame, a plurality of longitudinally disposed ribs on the frame one below and laterally spaced from another, superimposed corrugated strips extending between the upper side of each rib and the other side of the rib above, means to feed material to be concentrated upon the upper side of the deck, means to impart longitudinal movement to the deck and means beneath the said ribs to cause a gaseous medium under pressure to discharge through the laterally perforated means.

5. In a dry concentrating table a deck consisting of a transversely inclined frame, means to reciprocate the frame longitudinally, a plurality of laterally perforated, upwardly extending walls formed of corrugated strips supported on the frame the inner face of the upper portion of each wall contacting with the outer face of the lower portion of the wall above and the upper surface of each wall cooperating with the lower portion of the wall above to form a channel, means to supply a gaseous medium under pressure rearwardly of the walls, and means to feed material upon the deck, the perforations in the walls having communication with the gaseous medium and being adapted to conduct the same laterally through said walls and laterally through the upper portion of the channels.

6. In a dry concentrating table a trans-

versely inclined deck, means to reciprocate the deck longitudinally, the surface of the deck being formed in a series of longitudinal steps arranged at an angle to the direction of reciprocation of the deck, the treads of the steps being impervious and the risers having a plurality of lateral ducts extending diagonally through the same and an air box beneath the said surface to which

10 air under pressure is supplied, means to feed

material to be concentrated upon the deck, the material under the influence of gravity being caused to descend over the steps and the ducts being adapted to direct the air under pressure laterally through the descending material for moving the lighter particles laterally therefrom. 15

In witness whereof I have hereunto subscribed my name.

EMIL DEISTER.
